Wes. 1618

Elemir J. Ney, of Lowell, Mass.
Assignor to the
Lowell Manufacturing Company.
Letters Patent No. 1618, dated Aug. 5, 1862.

The schedule referred to in these Letters Patent and making part of the same.

To all whom it may concern:

Be it known that I, Elemir J. Ney, of Lowell, in the County of Middlesex and State of Massachusetts, have originated and designed a new pattern for carpets or other fabrics, of which the following is a full, clear and exact description, reference being had to the accompanying drawings, making part of this specification.

Fig. A, is a medallion with a scalloped border enclosing a garland of flowers. Within this garland is a ground of web work, supporting a rosette.

Figs. B and C, when matched, form combinations of gothic work surrounded by sprigs 2.2.

Space between figs B and C, is a figure D, having scroll outlines enclosing small lines or dots. Figs. 3 and 4, when matched, form a figure similar to D.

Connecting fig. A and figs B and C, respectively are the scrolls 5.5, 6.6. The remaining figures in the drawing are either repetitions or sections of figures similar to those before mentioned. An indented ground work occupies the space in the design not covered by the specified figures.

The colors employed for the different portions of the design may be varied to suit the taste and wish of the manufacturer.

Claim.

What I claim as my invention and desire to secure by Letters Patent, is the design or pattern, for carpets or other fabrics, herein set forth.

Witnesses.
